RADIO ANTENNA

Edward L. Barrett, La Grange, Ill.

Application September 8, 1941, Serial No. 410,024

7 Claims. (Cl. 250—33)

This invention relates to a new and improved radio antenna and more particularly to apparatus of this character which is extensible and retractable by force applied thereto in either direction.

While they are of broad application, antennae of this character are especially adapted for use in connection with radio receivers used upon automobiles. It is desirable to have the antenna down in its retracted position when the automobile is in a garage or passing where there are low obstructions, such as tree branches. It is also practical to receive nearby powerful stations with the antenna in its retracted position and many users normally maintain it in this position, except when traveling at a distance from transmitting stations. Many users, however, prefer to have the antenna normally extended to an intermediate position with its upper end not substantially above the car roof, since this position is effective for the larger portion of reception requirements and does not require retraction of the antenna when the car enters a garage.

The majority of such antennae now in use are manually operated by pulling or pushing on the upper antenna section. In most cases this cannot be conveniently done from inside the car and makes it necessary to stop the car and get out to adjust the antenna. Some antennae are power-operated as, for example, the apparatus shown in my prior Patent No. 2,299,785, October 27, 1942. The construction of the prior application is operable from the interior of the car, which avoids the above-mentioned objection. For some purposes, as stated above, however, it is not desirable to have an antenna which is either fully extended or retracted or which is automatically extended when the radio set is turned on. While a power driven unit can be operated with independent switch control and without limit switches so that it may remain at any desired adjustment, there are many installations in which the expense of power operating mechanism is not justified. The actual power necessary to move the antenna is small and it is consequently readily adaptable to remote control by means of manually operable apparatus.

Antennae, whether power operated or operated by hand by remote control means, should be capable of manual operation by direct grasp of the antenna itself. Both the user and other persons, such as garage attendants or mechanics, will attempt from time to time to raise or lower the antenna in this manner. Consequently, the

antenna and its operating connections must be designed so that they do not jam or get out of adjustment when the antenna is pushed down or pulled up.

5 An automobile radio receiver must be designed with a very high degree of sensitivity, since it operates with a comparatively small antenna and frequently operates in locations which are shielded and give poor radio reception. To function efficiently the input circuit must be matched to the antenna and consequently the antenna should have substantially uniform electrical characteristics regardless of its position of adjustment.

10 It is an object of the present invention to provide a new and improved type of collapsible antenna which is adapted for remote control by means of manually operated or power operated means.

15 It is a further object to provide an antenna of this character which is collapsible and extensible by means of force applied directly to the antenna itself.

20 It is also an object to provide apparatus of this character which may be freely adjusted to intermediate positions of extension.

25 It is an additional object to provide an antenna of this type which is smoothly and freely operable by application of relatively light manual power.

30 It is another object to provide an antenna having little variation in its electrical characteristics in different positions of adjustment and having no substantial variation in such constants with normal wear in use.

35 It is a further object to provide a construction in which the current carrying portions of the antenna are well insulated from the grounded portions of the structure, with relatively long leakage paths over intermediate insulation.

40 It is also an object to provide a construction which is simple in design and adapted for commercial production and use.

45 Other and further objects will appear as the description proceeds.

I have shown a preferred embodiment of my invention in the accompanying drawings, in which—

Figure 1 is a side elevation of the antenna and operating reel construction;

Figure 2 is a view of the construction of Figure 1 as seen from the right;

Figure 3 is a view similar to Figure 1 but on a reduced scale and showing the antenna in extended position;

Figure 4 is a vertical section on an enlarged

scale showing the reel and antenna assembly, the upper portion of the antenna being broken away:

Figure 5 is a transverse section taken on line 5-5 of Figure 4; and

Figure 6 is a section taken on line 6-6 of Figure 5.

In the drawings, referring first to Figures 1 to 3, the housing 11 encloses the reel or drum and is provided with the strap 12 by which it can be mounted upon any suitable support. This housing 11 also is provided with a bushing 13 through which the operating shaft may be connected. Directly connected to the housing 11 is a tubular fixed antenna housing 14, which is provided at its upper end with an insulating washer 15 which supports the lower fixed section 23 of the antenna proper in spaced relation to the antenna housing 14. As shown, the antenna comprises the slideable tubular antenna sections 16, 17 and 18 and the final antenna section 19 which consists of a solid rod.

Referring now to Figure 4, the lower fixed antenna section 23 is supported at its lower end in the insulating sleeve 20, which sleeve is provided at its lower end with a reduced section 21 entering into the housing 11. This section 21 extends well into the drum and provides a long leakage path between the housing and the antenna. This sleeve 20 is provided with a central cylindrical opening 22 through which passes the flexible member 23. This member 23 is connected at its upper end to the lower end of the antenna rod section 19. It will be noted that the lower end of this antenna section 19 is provided with an enlarged portion 24 by means of which it picks up the second antenna section 18, when the rod moves upwardly. The section 18 is also provided with a shoulder 25 which serves to pick up the next section 17. This section 17 is provided with a shoulder 26, serving to pick up the lower movable section 16. The section 16 is provided with a circumferential bead 27 at its lower end engaging the inner face of the fixed section 23 so as to prevent play and render the structure substantially rigid when extended.

The housing 11 is formed of metal and has a removable cover 31 as shown in Figures 2 and 5. The housing 11 has an opening in its side wall through which passes the shaft bearing member 32 which is held in place by nut 33. The bearing 32 has a shoulder engaging the washer 34 which holds a spring washer 35 against the insulating member 36. This member 36 may be formed of hard Bakelite or a similar insulating material. The member 36 is provided with a plurality of extended portions 37 which engage the inner face of the housing 11, but the main portion of its surface is spaced from the housing to provide a long leakage path from the antenna. It is provided with the lug 38 extending through the housing to locate the member positively in the housing. As shown in Figure 6, the member 36 is of a contour to fit within the housing but spaced from the housing walls, and is provided with the channel 43 having a flaring opening 41 adapted to receive the flexible member 23. The member 36 is shown in the drawings as reversible, having a second similar channel 42. This reversibility is merely in assembly, so that the reel construction can be used for right or left hand use, and has no function in the operation of the assembled reel.

The shaft bearing member 32 carries the rotatable reel shaft 44, to the inner end of which

are secured the substantially rigid securing washer 45 and the spring washer 46. The latter washer is shown as a Belleville spring and serves to frictionally clamp the insulating disc 47 against the fixed washer 45. These washers 45 and 46 together form a friction clutch engaging the insulating disc 47, permitting slippage in the event of excess pressure from either direction or binding of other parts in operation or in misuse.

10 The drum proper comprises the inner cylindrical wall member 48 and the outer cylindrical wall member 49. These members are spaced apart a distance slightly greater than the thickness of the flexible member 23. Members 48 and 49 are provided with radially extending flanges 50 and 51, respectively, which are fixedly secured to the insulating disc 47 by means of rivets or eyelets 52. It will be noted from Figure 5 that the outer drum member 49 has its free edge terminating short of the free edge of the member 48. The free edge 53 of member 48 is curved to form an outwardly extending flange adapted to receive the flexible member 23 in operation of the apparatus. The insulating member 36 is provided with a circumferential flange 54 extending opposite the free edge of the outer drum member 49.

15 A drive member 55 is shown as fitting into a slot formed in the rotatable shaft 44 and it will be understood that this member 55 may be connected to a flexible shaft or to an operating handle of any kind for rotation of the shaft. It will be further understood that the reel may be rotated manually or mechanically by any desired power drive, as the invention is independent 20 of the specific means or method of driving the shaft. The housing member 14 has an opening formed therein through which extends the shielded cable 60, the conducting member 61 of the cable being shown as soldered at 62 to the lower fixed portion 23 of the antenna. It will be understood that the cable 60 is connected in any desired manner to the radio apparatus using the antenna.

25 In the use of the antenna it may be extended and retracted merely by manually applying force to the upper rigid portion 19 of the antenna. When pulled outwardly, the flexible member 23 passes freely from the reel, passing out between the free ends of inner and outer reel members 30 48 and 49. It will be understood that in order for this to happen, the reel must rotate, as the inner end of the member 23 is fixedly secured to the reel as indicated by numeral 63, Figure 5. This connection of the flexible member 23 to the drum is located at a point spaced from the free edges of the drum. If the shaft or other drive means connected to the rotating shaft 44 of the drum is free to permit such reverse movement, the entire assembly will rotate. If the 35 drive is not reversible, upon drawing out the antenna manually the drum elements 48 and 49, together with the insulating disc 47, will slip through the friction clutch formed by the rigid disc 45 and the spring disc 46, and the shaft and its associated parts will remain still. The drive required to operate the antenna is light so that this friction clutch need not have such a heavy grip as to cause such manual operation to require an undue amount of force. As the antenna 40 is moved upwardly, the flexible member 23 is guided by means of the channel 43 in insulating member 36 and guided through insulating collar 20. The convolutions progressively move toward the free open end of the drum channel and interpose no substantial resistance to this movement.

Similarly, when the antenna is pushed down, the flexible member 23 is guided in the reverse direction and the convolutions gradually become closer together in the drum space. Adequate drum area is provided so that there is no binding when the antenna is completely collapsed.

In the operation of the antenna, by rotating the shaft 44 the sections are forced upwardly or drawn downwardly by flexible member 23, which feeds out of or into the reel space between the drums as shaft 44 is rotated. Continuing to apply power to the shaft after movement is completed in either direction will not injure the parts or cause jamming, since slippage will then occur between the insulating disc 47 and the associated friction clutch.

It is to be noted that the antenna elements and the flexible member 23 are connected in the electrical input circuit of the receiver with which the antenna is used, and consequently must be insulated from ground. The insulating disc 47 partially serves this purpose and the insulating member 36 completes insulation within the housing. The collar 20 serves to insulate the lower fixed section of the antenna and the adjacent portion of flexible member 23 from the housings 11 and 14. The insulating member 36 provides a relatively long leakage path between the point of contact of the member 23 therewith and the points of contact between that member 36 and the housing 11. Further, even though the member 23 be lubricated, as it will be in normal use, there is no tendency for this lubricant to flow over insulating surfaces.

The drum surfaces which contact the member 23 are rounded and consequently there is little wear at their points of contact and the apparatus will have long life without deterioration. The capacity between the metal drum members 48 and 49 and the grounded housing members is constant regardless of the portion of member 23 which may be within the reel. The capacity between the lower fixed section 23 of the antenna and the housing member 14 is also constant. Therefore, there is very little variation in the capacity of the antenna regardless of its position. The capacity is only slightly higher in extended position, because some of the antenna surface is exposed to adjacent car parts, but the capacity within the antenna structure itself is substantially constant.

While I have shown a preferred embodiment of my invention it is to be understood to be illustrative only, as it may be modified to meet differing conditions and requirements, and I contemplate such variations as come within the spirit and scope of the appended claims.

What is claimed is:

1. In combination with a radio antenna comprising fixed and movable elements, a flexible member connected to the movable element, said flexible member being capable of applying a thrust or a pull to the movable member, a drum having inner and outer substantially cylindrical walls fixedly secured together and spaced apart a distance slightly greater than the thickness of the flexible member, the walls having free edges on one side of the drum, the inner wall having an outwardly extending flange extending axially beyond the outer wall, the wall edges being spaced apart a distance slightly greater than the thickness of the flexible member, one end of the flexible member being secured to the drum between the walls at a point spaced from their free edges, and means rotatably supporting the drum.

2. In combination with a radio antenna comprising fixed and movable elements, a flexible member connected to the movable element, said flexible member being capable of applying a thrust or a pull to the movable member, a metallic drum having inner and outer substantially cylindrical walls fixedly secured together and spaced apart a distance slightly greater than the thickness of the flexible member, the walls having free edges on one side of the drum spaced apart a distance slightly greater than the thickness of the flexible member, one end of the flexible member being secured to the drum between the walls at a point spaced from their free edges, insulating means for guiding the flexible member into the space between the drum walls, and means rotatably supporting the drum.

3. In combination with a radio antenna comprising fixed and movable elements, a flexible member connected to the movable element, said flexible member being capable of applying a thrust or a pull to the movable member, a drum having inner and outer substantially cylindrical walls fixedly secured together and spaced apart a distance slightly greater than the thickness of the flexible member, the walls having free edges on one side of the drum, the inner wall having an outwardly extending flange extending outwardly over the space between the walls, the wall edges being spaced apart a distance slightly greater than the thickness of the flexible member, one end of the flexible member being secured to the drum between the walls at a point spaced from their free edges, a rotatable shaft for the drum, and a frictional clutch connecting the drum and shaft.

4. In combination with a radio antenna comprising fixed and movable elements, a flexible member connected to the movable element, said flexible member being capable of applying a thrust or a pull to the movable member, a metallic drum having inner and outer substantially cylindrical walls fixedly secured together and spaced apart a distance slightly greater than the thickness of the flexible member, the walls having free edges on one side of the drum spaced apart a distance slightly greater than the thickness of the flexible member, one end of the flexible member being secured to the drum between the walls at a point spaced from their free edges, a rotatable shaft for the drum, and insulating means connecting the shaft and drum.

5. In combination with a radio antenna comprising fixed and movable elements, a flexible member connected to the movable element, said flexible member being capable of applying a thrust or a pull to the movable member, a metallic drum having inner and outer substantially cylindrical walls fixedly secured together and spaced apart a distance slightly greater than the thickness of the flexible member, the walls having free edges on one side of the drum spaced apart a distance slightly greater than the thickness of the flexible member, one end of the flexible member being secured to the drum between the walls at a point spaced from their free edges, a rotatable shaft for the drum, and an insulating disc extending between the drum and shaft, and a frictional driving connection between the shaft and insulating disc.

6. In combination with a radio antenna comprising fixed and movable elements, a flexible member connected to the movable element, said flexible member being capable of applying a thrust or a pull to the movable member, a drum having inner and outer substantially cylindrical

metallic walls fixedly secured together and spaced apart a distance slightly greater than the thickness of the flexible member, the walls having free edges on one side of the drum spaced apart a distance slightly greater than the thickness of the flexible member, one end of the flexible member being secured to the drum between the walls at a point spaced from their free edges, insulating means rotatably supporting the drum, and a housing for said drum, said housing having an opening therein, insulating means for guiding the flexible member through the opening and into the drum, said insulating means substantially closing the opening between the free edges of the drum walls.

7. In combination with a radio antenna comprising fixed and movable elements, a flexible member connected to the movable element, said flexible member being capable of applying a thrust or a pull to the movable member, a metallic drum having inner and outer substantially cylindrical walls fixedly secured together and

spaced apart a distance slightly greater than the thickness of the flexible member, the walls having free edges on one side of the drum spaced apart a distance slightly greater than the thickness of the flexible member, one end of the flexible member being secured to the drum between the walls at a point spaced from their free edges, a metallic housing for the drum spaced from the drum walls, a rotatable shaft carried by the housing, insulating means connecting the shaft and drum, the housing having an opening therein, insulating means carried by the housing for guiding the flexible member through the opening, and an insulating member carried within the housing and contacting the housing only at spaced points, the insulating member guiding the flexible member into the drum, said insulating member being located adjacent to and substantially closing the opening between the free edges of the drum walls.

EDWARD L. BARRETT.
